(57) **CLAIM**

The ornamental design for a phone case, as shown and described.

DESCRIPTION

FIG. 1 is a front elevational view of a phone case showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view of the phone case where the phone case is in a fully folded state;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a left side elevational view of the phone case where the phone case is in a first configuration of use;

FIG. 16 is right side elevational view thereof;

FIG. 17 is a perspective view of the phone case where the phone case is in a second configuration of use; and,

FIG. 18 is another perspective view thereof.

The broken lines in the drawings depict portions of the phone case that form no part of the claimed design.

1 Claim, 18 Drawing Sheets
